(57) CLAIM

The ornamental design for a construction toy, as shown and described.

DESCRIPTION

FIG. 1 is a front, left and bottom perspective view of a construction toy showing my new design;

FIG. 2 is a rear, left and top perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof; and,

FIG. 9 is a sectional view thereof, taken in the direction of 9-9 in FIG. 3.

The broken lines in the drawings illustrate the portions of the construction toy that form no part of the claim.
